UNITED STATES PATENT OFFICE.

GEORGE T. BATES, OF ELGIN, ILLINOIS, ASSIGNOR TO ILLINOIS WATCH CASE COMPANY, OF ELGIN, ILLINOIS, A CORPORATION OF ILLINOIS.

VANITY CASE.

Application filed June 3, 1925. Serial No. 34,514.

To all whom it may concern:

Be it known that I, GEORGE T. BATES, a citizen of the United States, residing at Chicago, in the county of Cook and State of Illinois, have invented certain new and useful Improvements in Vanity Cases, of which the following is a specification.

This invention which relates to a vanity case is concerned particularly with the provision of a compartment for loose powder, with means for opening certain slits through which the powder may be shaken therefrom, and with means by which a filling opening may be uncovered for the introduction into the powder compartment of a new supply of material. It is with objects such as these, as well as others which will hereinafter appear that the present invention is concerned.

20 An embodiment of my invention in a preferred form is set forth in the accompanying drawing in the manner following:

Figure 1 is a perspective view of a vanity case with the cover opened to expose the shaker plate;

Fig. 2 is a plan view of the case with the shaker plate removed;

Fig. 3 is an enlarged transverse section taken through the case on line 3—3 of Fig. 1;

Fig. 4 is a detail in plan of the shaker plate per se;

Fig. 5 is a sectional detail taken on line 5—5 of Fig. 1; and

35 Fig. 6 is a fragmentary plan view of a case to which the shaker plate is additionally connected by a hinge.

I have shown in the drawing a case A with a bottom 7 from which upstand side walls 8 of any desired contour. Associated with such a case is a cover B, connected thereto, if desired, by a hinge 9. Mounted in the cover is a mirror 10 which may be held in place by a ring 11 inwardly extended from the cover side walls. Any suitable catch 12 may be employed to hold the cover releasably in closed position upon the seat.

50 Fitted within the case is a frame C, preferably of sheet metal, comprising a top 13 having depending marginal side walls 14 which fit closely within the walls of the case. An opening 15 is provided in the marginal walls of the frame to co-operate with the catch 12. By means of a cross wall 16 (see Fig. 2) which is positioned adjacent

this opening, I partition off a compartment which lies beneath the top 13 and the case bottom. Such a compartment is adapted to accommodate a supply of loose powder.

The frame top is inwardly dished or depressed to form a circular seat for a shaker plate 17. Extending upwardly through the center of the frame top is a pivot pin 18 which carries on its upper side a circular hub 19 from which extend a pair of fingers 20. This hub is receivable within a circular aperture 21 of the shaker, the same being provided with a pair of oppositely extended slots 22, as best shown in Fig. 4. By the means described, I provide a releasable pivotal connection in the form of a turn button between the shaker plate and the frame top. In putting the shaker in place, the fingers 20 are first turned into alignment with the slots 22 whereupon the shaker plate will seat properly. To lock the plate in position, the fingers 20 are then turned around, perhaps 90 degrees, as shown in Fig. 1. The shaker is thereupon attached to the frame top in a manner which will be secure at all times.

Formed through the shaker are a plurality of openings 23 which preferably take the form of slits. These are adapted to register with corresponding openings 24 in the frame top when the shaker is rotated properly for this purpose. These movements are facilitated by one or more catches 25, preferably two in number, and each desirably formed by a depending indentation in the shaker plate. As shown, the two catches are arranged relatively near to each other, and on that side of the plate which is proximate to the hinge connection 9. Beneath the two catches, the frame top is cut away to provide an opening 26 through which a fresh supply of powder may be introduced into the case. By arranging the opening 26 in this relation to the two catches, I provide a means of limiting the rotary movement of the shaker for the reason that these catches will successively engage with an edge 27 of this opening whenever the shaker has been moved into a position which opens or closes the slits 24.

105 From the preceding description it will be apparent that the case may be carried about with the shaker adjusted to its closed position so that no powder can escape. If it is desired to release some of the powder, a fin-

ger pressure is applied to one of the catches whereupon the shaker is turned to open the slits 24. This position is reached when one of the catches is in contact with the edge 27 which borders the opening 26. After spilling out a quantity of the powder, the shaker is again rotated, but in an opposite direction with the result that when its limit of movement has been reached, the slit openings 24 will be closed. The removal of the shaker for replenishing the case with powder requires merely that the fingers 20 be rotated into alignment with the slots 22, whereupon the shaker can be lifted from its seat.

15 The construction shown in Fig. 6 is a modification only to the extent that the shaker is additionally connected to the frame top by a hinge 28. When the case is to be replenished with a new supply of powder, the shaker is disconnected at the pivot, and then swung back upon its hinge. A necessary characteristic of this hinge connection is that it should permit the shaker to slip sufficiently so as to rotate on its pivot within the movement limits which are defined by the two catches 25 engaging with the edge 27 of the opening 26.

20 A case of the kind described should preferably be made to accommodate a puff 29, and for this purpose a sufficient clearance has been provided between the shaker plate and the mirror 10, as shown in Fig. 3. It will be apparent that the case may be used without any danger of accidental escape of the loose powder contained therein, owing to the simple and effective means provided for holding the shaker-closure in place.

25

I claim:

1. A vanity case in which is a top plate 40 with a seat therein, a circular shaker plate mounted on the seat, there being openings in the two plates adapted to register when the

shaker plate is rotated to a predetermined position, and a detachable pivotal connection between the two plates comprising a pin carried by the one and extended through an opening in the other, there being a pair of slots oppositely extended from the opening, and a hub carried by the pin adapted to enter the plate opening, there being a pair of fingers extended from opposite sides of the hub in a manner to pass through the slots in the plate opening and when turned relative therethrough, to secure the one plate to the other, substantially as described. 55

2. A vanity case in which is a top plate with a seat therein, a circular shaker plate mounted on the seat, there being openings in the two plates adapted to register when the shaker plate is rotated to a proper position for this purpose, a detachable pivotal connection between the two plates, and means on the shaker plate co-operating with a portion of the top plate which is concealed by the former to limit the rotary movement thereof, said means also being engageable by the finger to facilitate rotation of the shaker plate, substantially as described. 60

3. A vanity case in which is a top plate having a seat, a shaker plate mounted with in the seat, there being a filling opening in the top plate beneath the shaker plate and also other smaller openings in both of said plates adapted to register when the shaker plate is rotated to a proper position for this purpose, a detachable pivotal connection between the two plates, and stop means for limiting rotary movements of the shaker plate including a part depending therefrom into the filling opening adapted to engage with opposite edges thereof, substantially as 65 70 75 80 85 described.

GEO. T. BATES.
